UNITED STATES PATENT OFFICE.

OTTO K. NESTE, OF MADISON TOWNSHIP, WINNESHEK COUNTY, IOWA.

POST-HOLE DIGGER.

No. 819,791.

Specification of Letters Patent.

Patented May 8, 1906.

Application filed September 19, 1905. Serial No. 279,104.

To all whom it may concern:

Be it known that I, OTTO K. NESTE, residing in Madison township, county of Winnesheik, and State of Iowa, have invented a new and Improved Post-Hole Digger, of which the following is a specification.

My invention relates to improvements in that type of digging implements having a stationary penetrating blade secured upon the lower end of a handle and an adjustable blade or scoop member that coacts with the other blade and is adapted to be closed in over the lower end of the other blade whereby to form a receiver for pulling the earth out of the hole during the operation of digging; and primarily my invention seeks to provide an implement of the character stated of a simple and inexpensive nature which can be readily manipulated and which will effectively serve its intended purposes.

My invention consists in certain details of construction and combination of parts hereinafter fully described, specifically pointed out in the appended claims, and illustrated in the accompanying drawings, in which—

Figure 1 is a perspective view which illustrates the manner in which my digger is used. Fig. 2 is a vertical section of the same, showing the blades in position of being forced into the ground. Fig. 3 is a similar view showing the adjustable blade swung over the other blade to form a receiver or dirt-holder. Fig. 4 is a horizontal section taken on the line 4-4 on Fig. 2. Fig. 5 is a perspective of the two blade or scoop members detached.

In the drawings, in which like letters indicate like parts in all the figures, *a* designates a pole or handle-bar of suitable length, on the lower end of which, at opposite sides thereof, are bolted or otherwise made fast a pair of angle-iron brackets *b b*, to whose lower ends is rigidly secured a semicircular stout metal band *c*, to which the semicircular or concaved blade or scoop member *d* is fixedly secured and which extends down from said band in a plane parallel with the handle-bar, and said blade (as also the opposite blade *e*, presently again referred to) has the lower end curved to easily penetrate the ground.

The blade *e*, which is shaped the same as the blade *d*, is adjustably mounted with respect to the other blade and is of a slightly-greater diameter, so that when it is moved in toward the blade *d* its lower edges will close over the opposing edges of the said blade *d*. The blade or scoop member *e* is firmly se-

cured by riveting or otherwise to a stout metal strap or band *f*, the opposite ends of which are extended to form side arms *f'*, projected into the concavity of the opposite blade and then bent inwardly toward each other to form a bifurcated bearing *f''*, adapted to receive the lower end of the actuating-rod *g*, fulcrumed at said lower end upon the stud *h*, that passes through the rod-eye *g'* and the apertured bearing *f''*.

By referring now more particularly to Fig. 4 it will be noticed that while the stationary blade or scoop is primarily braced and held firmly to its position by the band to which it is attached and by reason of the latter being firmly riveted to the lower ends of the brackets *b b* the bifurcated ends of the other band are of such length that when the two blades are in parallel plane—that is, in position for digging—the said bracket ends form an additional brace for the upper end of the stationary blade by bearing against the inner face of the band *c*, and by reason thereof the strain on the pivot-bolt *k*, that passes through the brackets *b b*, the bands *c* and *f*, and the lower end of the handle is also reduced, since it is distributed to both sides thereof. To provide for the swinging adjustment of the blade *e* and maintain a close bearing with the band *c*, the ends of the band *f* are curved on an arc with the bolt *k* as the center. The actuating-rod *g* extends up along one side of the bar *a* and connects with a bell-crank lever *j*, fulcrumed on the handle *a*, and whose long arm or handle *j* extends up to the top or handle end of the bar *a*, as shown.

From the foregoing, taken in connection with the accompanying drawings, the construction and the manner in which my invention is used will be readily apparent.

By reason of the peculiar construction and arrangement of the parts as stated and shown I have provided a compact and durable digger device. In practice the operator firmly grasps the two handle members together, which firmly holds the two blades in parallel vertical planes and in position to be forcibly entered into the ground, and owing to the manner in which the upper ends of the two blades are secured and braced relatively to each other and the handle-bar the danger of the blades spreading or buckling outwardly is reduced to the minimum. To lift out the dirt, the blade *e* is swung inwardly with its lower end closed over the other blade, which operation is effected by simply pulling

the handle end of the bell-crank lever to the position shown in Fig. 3.

Having thus described my invention, what I claim, and desire to secure by Letters Patent, is—

- 5 1. In a post-hole digger of the character described, the combination with the handle-bar, the angle-brackets secured to the lower ends thereof, the curved band fixedly secured to the lower ends of the said brackets and the scoop or blade fixedly secured to the said band; of a second curved band pivotally supported on the lower ends of the handle-bar and the angle-brackets, the blade 10 member fixedly secured to the pivoted band, said pivoted band having its free ends extended up to the inner face of the fixedly-held band, a pivot carried by said ends, a bell-crank lever on the upper end of the handle-bar, and a link-rod connected at its lower 15 end to the pivot member on the outer ends of the pivoted band, and at the upper end to the bell-crank lever, substantially as shown and for the purposes described.
- 20 2. The combination with the handle-bar,

the angle-brackets secured to the opposite sides of its lower end, the curved band fixedly secured to the lower ends of the said brackets and the blade or scoop member fixedly secured to the said fixedly-held band; 30 of the second curved band having side arms pivotally mounted on the lower ends of the brackets, said arms having their ends bent inwardly toward each other to form a bifurcated bearing, a pivot-pin mounted on said bifurcated bearing, the outer end of said side arms being disposed in close relation to the inner face of the fixedly-held band and curved on an arc with the fulcrum of the said pivoted band as the center, the blade fixedly secured to the pivoted band, the bell-crank lever on the band and the link connection that joins the bell-crank lever and the bearing on the ends of the pivoted band, substantially 35 as shown and described.

OTTO K. NESTE.
